UNITED STATES PATENT OFFICE.

FRANK ALBACH, OF ST. LOUIS, MISSOURI, ASSIGNOR TO FRED MEDART MANUFACTURING COMPANY, OF ST. LOUIS, MISSOURI, A CORPORATION OF MISSOURI.

CABINET AND LOCKER.

Application filed June 20, 1927. Serial No. 199,964.

This invention relates to plate metal cabinets and lockers of the type adapted for the reception and safe keeping of articles of clothing, outfits and other accessories, in the dressing rooms of golf courses and like grounds, halls, etc., and the present improvement has for its object:

To provide a structural formation and association of parts and features in the above mentioned type of cabinets and lockers, providing a plurality of side shelves, hanger rails, clothes hooks and one or more closed compartments, adapted to receive in convenient and readily accessible manner the articles of clothing, outfits, etc., of an individual all as will hereinafter more fully appear.

In the accompanying drawing:—

Fig. 1, is a front elevation of a cabinet or the like embodying the present invention, parts being shown broken away and in section.

Fig. 2, is a vertical section on line 2—2 Fig. 1.

Fig. 3, is a horizontal section on line 3—3 Fig. 1.

Fig. 4, is an enlarged fragmentary section on line 4—4 Fig. 2, showing the formation of a closed compartment and its sliding door, in the interior of the structure.

Like reference numerals indicate like parts in the different views.

The preferred form of the present cabinet or like structure, as shown in the drawing, is of the rectangular vertically elongated type generally used in club and like rooms, and comprising a plate metal front wall 1, rear wall 4, side walls 5, and top and bottom walls 6 and 7, fixedly connected together in any usual and suitable manner to constitute a rigid unit or structure.

In the present construction, the entry or doorway is formed in the front wall 1 and extends approximately the full height of such wall to provide a narrow vertical jamb or upright 2, at one side of the doorway and a widened vertical jamb or upright 3, at the opposite side of said doorway for the purpose hereinafter set forth. The door 8 for such doorway is preferably hinged to the widened jamb or upright 3 aforesaid as shown.

A material part of this invention, in connection with the above described wide formation of the jamb 3 of the structure, com-

prises a plurality of shelves 9 of a trapezoidal form, arranged in the following manner:—

The forward and narrow end of each trapezoidal shelf 9 is of a width approximating 60 the width of the aforesaid jamb 3 and has fixed association with the inside face of said jamb; the rear and wider end of said shelf is parallel with said forward end and has fixed association with the rear wall 4 of 65 the structure; one side end of said shelf is in right-angle relation to the rear end aforesaid, and has fixed association with a side wall 5 of the structure, while the opposite side end of said shelf is oblique to the other 70 three ends of the shelf as illustrated in Fig. 3. With such construction and arrangement, a storage chamber of a complementary trapezoidal form in horizontal section, extending the full height of the structure is 75 left, the same providing a maximum storage capacity for hanging garments and the like, with a minimum width of a cabinet or locker structure, and is intended to meet a very necessary requirement in the locker rooms of 80 golf and like clubs, of a minimum horizontal area of individual lockers, with maximum storage capacity in each, and with the end in view of the use of a maximum number of the lockers on a given floor space. 85

With a view to convenient storage of clothing, etc., in the vertical storage chamber above described, the under face of the top wall 6 will carry a horizontal hanger rail 10 for such clothing suspension, and for a like purpose the side wall 5, remote from the shelves 9, will be provided with a horizontal row of clothes hooks 11, as shown in Figs. 1 and 3.

Another material part of the present improvement involves the formation between two adjacent shelves 9, of a closed closet or chamber for the reception of articles of value, etc., and to such end consists in the formation of a guide groove 12 in the under face of one shelf 9, adjacent to the oblique edge of the same, and the formation of a complementary guide groove 13 in the upper face of the next lowermost shelf 9.

The grooves 12 and 13 are adapted to form 105 a trackway in which the respective upper and lower ends of a sliding door 14 is adapted to have movement to cover and uncover the forward portion of the cavity between the pair of shelves 9.

In the preferred construction shown in Fig. 4, the sliding door 14, is formed of place metal having a flanged or reinforced border provided with top and bottom cylindrical bead or folds 15 adapted for sliding engagement in the above described guide grooves 12 and 13. In such construction the rear portion of the described shelf cavity is closed by a vertical partition 16 secured to 10 the oblique edges of the pair of shelves 9 aforesaid, in offset relation to the sliding door 14.

The inner face of the drain door 8 of the present structure affords a convenient location for the attachment of a holding pin 17 15 for golf balls, or like smaller articles.

Having thus fully described my invention, what I claim and desire to secure by Letters Patent is:—

- 20 1. In a locker of the type described, the combination of a rectangular enclosing casing comprising a front wall, side walls, a rear wall and top and bottom walls, the front wall having a doorway arranged to one side 25 of the wall to provide a narrow vertical jamb at one side of the doorway and a wide vertical jamb at the other side, and a plurality of shelves having a trapezoidal form, with the forward and narrow end of each 30 shelf having a width approximating the width of the aforesaid wide jamb and attached to the inner face of same, one side edge and a rear edge of each shelf having attachment to a side and rear wall of the 35 locker casing, and the other edge of each shelf having an oblique position in said casing, the combination providing a clear vertical storage space between the plurality of shelves and a remote side wall of the casing 40 of a maximum capacity in a minimum width of the casing.

2. In a locker of the type described, the combination of a rectangular enclosing cas-

ing comprising a front wall, side walls, a 45 rear wall and top and bottom walls, the front wall having a doorway arranged to one side of the wall to provide a narrow vertical jamb at one side of the doorway and a wide vertical jamb at the other side, and a plurality of shelves having a trapezoidal 50 form, with the forward and narrow end of each shelf having a width approximating the width of the aforesaid wide jamb and attached to the inner face of same, one side edge and a rear edge of each shelf having 55 attachment to a side and rear wall of the locker casing, and the other edge of each shelf having an oblique position in said casing, the oblique edges of a pair of the shelves having guideways, and a sliding door moving in said guideways.

3. In a locker of the type described, the combination of a rectangular enclosing casing comprising a front wall, side walls, a rear wall and top and bottom walls, the front wall having a doorway arranged to one side of the wall to provide a narrow vertical jamb at one side of the doorway and a wide vertical jamb at the other side, and a plurality of shelves having a trapezoidal 65 form, with the forward and narrow end of each shelf having a width approximating the width of the aforesaid wide jamb and attached to the inner face of same, one side edge and a rear edge of each shelf having attachment to a side and rear wall of the locker casing, and the other edge of each shelf having an oblique position in said casing, the oblique edges of a pair of the shelves 70 having guideways, a sliding door moving in said guideways, and a vertical wall fixedly attached to the rear portions of said pair of shelves in offset relation to said sliding door.

In testimony whereof I affix my signature.
FRANK ALBACH.
